[75] Inventor: **Tomohisa Shimazu**, Shiroyama, Japan

Primary Examiner—Brian N. Vinson
Attorney, Agent, or Firm—Ladas & Parry

[73] Assignee: **Tokyo Electron Limited**, Tokyo-To, Japan

[57] **CLAIM**

[**] Term: **14 Years**

I claim the ornamental design for a heat retaining tube base for use in a semiconductor wafer heat processing apparatus, as shown and described.

[21] Appl. No.: **83,718**

DESCRIPTION

[22] Filed: **Feb. 12, 1998**

[30] **Foreign Application Priority Data**

Aug. 20, 1997 [JP] Japan 9-65105

FIG. 1 a perspective view of a heat retaining tube base for

[51] **LOC (6) Cl. 13-03**

FIG. 2 a front elevational view thereof;

[52] **U.S. Cl. D13/182**

FIG. 3 a top plan view thereof;

[58] **Field of Search D13/182; D15/144,**

FIG. 4 a right side view thereof;

D15/144.1, 199; 414/935-941, 217, 147;

FIG. 5 a bottom plan view thereof; and,

437/247, 946; D6/407, 629

FIG. 6 a cross-sectional view taken along line VI—VI in
